US0D1077465S

(12) United States Design Patent (10) Patent No.: US D1,077,465 S
(45) Date of Patent:  Jun. 3, 2025

(54) HANDBAG

(71) Applicant: CARTIER INTERNATIONAL AG,
Steinhausen (CH)

(72) Inventor: Kim TaeEun, Paris (FR)

() Term: 15 Years

(21) Appl. No.: 35/519,434

(22) Filed: Sep. 20, 2023

(80) Hague Agreement Data

Int. Filing Date: Sep. 20, 2023

Int. Reg. No.: DM/232172

Int. Reg. Date: Sep. 20, 2023

Int. Reg. Pub. Date: Dec. 22, 2023

(30) Foreign Application Priority Data

Mar. 24, 2023 (WO) WIPO130681

(51) LOC (15) Cl. 03-01
